13 INVENTOR.
Edwin L. Reinholdt
John Prelli

ATTORNEY.

UNITED STATES PATENT OFFICE.

EDWIN G. REINHARDT, OF CINCINNATI, OHIO.

SHOWER-BATH DOOR.

Application filed June 2, 1922. Serial No. 565,498.

The object of my invention is to produce a comparatively cheap, simple, and highly efficient door made from metal and glass, to be used as what is known as a shower bath door, and another object is to displace the canvas curtains now in general use for the purpose of retaining the water in the shower booth.

My invention further offers proper sanitary conditions which do not exist in the use of canvas curtains, and I further reduce the cost of the construction of the metal frame work of the metal and glass shower bath door.

The present frame of the shower bath door now in use is formed of built-up square tubing or rectangular tubing, which is costly and unsatisfactory. In the construction of my new door I employ an especial drawn flanged tubing of steel, copper, or brass, and thus make the frame work dependable, standard, and workman-like in appearance, and I usually insert a $\frac{1}{16}$ inch crystal glass in rubber gaskets, for supporting and retaining the glass; my unique, specially drawn tubing also forming a support for said glass.

The object and features of my invention will readily become apparent from a perusal of the following specification, to which reference is hereby made.

In the accompanying drawing forming part of this specification:

Fig. 1, is a front elevation of one side of my new door,

Fig. 2, is a similar view of the opposite side thereof,

Fig. 3, is a section on line 3—3 of Fig. 2,

Fig. 4, is a view of the bottom edge of the door,

Fig. 5, is a section on line 5—5 of Fig. 1,

Fig. 6, is a section on the line 6—6 of Fig. 1,

Fig. 7, is a section on line 7—7 of Fig. 1,

Fig. 8, is a section on line 8—8 of Fig. 1,

Fig. 9, is a section on line 9—9 of Fig. 1,

Fig. 10, is a section on line 10—10 of Fig. 1, and

Fig. 11, is a corner detail in elevation of the upper grille.

The door shown in the drawings is of a rectangular form its top and bottom and its two sides being formed like a metal framework joined at the meeting corners. The top is marked 1, the bottom 2, and the sides 3 and 4.

The parts 1, 2, 3, and 4, are made of hollow tubing, of the peculiar shape shown in Figs. 5, 6, 7, 8, and 9. This peculiarly shaped tubing is outlined by lines marked 5, 6, 7, 8, and 9, forming approximately a square outline with a hollow wing or rib 10 extending therefrom.

The corners formed by the hollow tubing 1, 2, 3, and 4 is as follows: An angle 31 is inserted into the end of one of said tubes 65 and the other end of the angle into the meeting tube and fastened securely together by rivets or screws 32 (see Fig. 11). Against side 8 of this tubing I place a bead or abutment 12, and between this abutment 70 and the side 9 of the tubing, I place a U-shaped rubber gasket or retainer 13, into which is forced the glass 14, which makes the door panel; this construction makes a tight joint.

At the top I provide an open grille work formed of bars 15 for ventilating purposes between the bars. The lower frame 17 which supports the grille consists of cross piece or bar 18, reinforced by side plates 80 19 and 20. The upper edge of glass panel 14 enters a rubber gasket 21 formed similarly to gasket 13, and this gasket 21 is held between the plates 19 and 20.

On one side of the door, the inside, I 85 provide a curved water shedding strip 16, for carrying off the water which might have a tendency to enter the adjoining room.

The door jamb is marked 22, and the door is hinged to one side thereof as shown by 90 a continuous hinge 23. This hinge may be connected between the door and jamb in any preferred manner. In the present instance the part 24 of the hinge is fastened to part 8, of the square tube, and the part 95 25 of the hinge is fastened to part 26 of the door frame or jamb 22, see Fig. 7.

In order to keep the door closed, I provide a friction catch formed of a sleeve 27 and a plunger 28, and a head 29, which is held in a position to allow of backward movement when the door is closed to tightly impinge against the door holding same closed by friction (see Fig. 9); by pressing against the door it will readily open, because the frictional contact will be broken.

A handle or pull bar 30 is used for opening and closing the door, in any preferred manner.

It will be noticed and understood that the 110

abutment or wing 9 is also for strength, although may be differently formed and that it is integral with the main hollow tube; that it forms one abutment for the 5 rubber gasket 13, and the glass 14, so that it is only necessary to place upon the opposite side of the same the bead or abutment 12, forming a unique construction and saving time and labor. This wing, rib or 10 flange 9 also adds strength to the hollow tube or pieces, and enhances the appearance of the construction.

In order to water-proof and rust-proof the door, I use a dipping process by 15 immersing the metal in oil.

While I have described one specific way and means of constructing my new shower bath door, it will be perfectly obvious that 20 the same is capable of some change and modification without departing from the spirit and principle of the invention, and I wish to be understood as claiming any such

modification which will still fall within the scope of my invention.

What I claim as new and my invention 25 and desire to secure by Letters Patent is:—

In a shower bath door of the class described, a metallic outside frame formed of hollow tubing lengths, said hollow tubing lengths provided with integral flanges extending therefrom, rubber gaskets and a glass panel, said glass panel fitting between the rubber gaskets, removable strips for holding the gaskets and glass panel in position, the metal flanges forming an abutment for 35 the gaskets and panel, a grille construction at the upper end of said door and a cross piece for supporting the same, said cross piece having plates on each side thereof which extend below the said cross piece, a 40 rubber gasket arranged between said plates and the door panel extending in to said last mentioned gasket to form a tight joint.

EDWIN G. REINHARDT.
